UNITED STATES PATENT OFFICE.

EMORY S. ENSIGN, OF ROCKFORD, ILLINOIS, ASSIGNOR TO SPENGLER LOOMIS MFG. CO., OF CHICAGO, ILLINOIS, A CORPORATION OF ILLINOIS.

CHIP-RECEPTACLE AND ART OF PRODUCING SAME.

1,390,517.

Specification of Letters Patent. Patented Sept. 13, 1921.

Application filed March 14, 1921. Serial No. 452,016.

To all whom it may concern:

Be it known that I, EMORY S. ENSIGN, a citizen of the United States, residing at Rockford, in the county of Winnebago and 5 State of Illinois, have invented certain new and useful Improvements in Chip-Receptacles and Art of Producing Same, of which the following is a specification.

This invention relates to pencil sharpeners, and particularly to chip receptacles therefor.

It has long been proposed to construct a chip receptacle of a pair of spaced framing members with connecting rods, bars, or the 15 like, to render them mutually sustaining, and to fit between said framing members, in position to form a side wall of the receptacle, a strip or collar of thin material readily conformable to the outline of the 20 framing members and held in confinement by the flanges thereof. Made first of thin sheet metal with a window at top to permit inspection of the working mechanism, this strip or collar was later made of celluloid 25 to render it transparent throughout. But exposure of the entire area of the wall to transparency is objectionable for several reasons, among which are conspicuousness of unsightly accumulation of chips and 30 graphite dust, eventual abrasion and murky appearance of the celluloid after protracted impingement of the cuttings, and general lack of ornamentation.

The present invention overcomes the objections stated and adds greatly to the ornamentation and salability of the pencil sharpener by providing upon a part or all, preferably a part, and leaving unobscured the window forming portion of the transparent 40 wall of such a chip receptacle, a backing sheath of pigment, for example, printers' ink, positioned on that part of the area which receives the impingement of the cuttings, and preventing abrasion and dulling 45 of the inner surface of the transparent material, while at the same time rendering non-transparent the area to which it is applied and showing its color through the transparent wall, backing up and rendering 50 more conspicuous any inscription, design, or ornamental figure placed thereon in advance, and taking on a brilliant surface gloss from the inherent nature of the transparent material, and, withal, greatly enhancing the 55 attractiveness and salability of the article.

In the accompanying drawing—

Figures 1 and 2 represent two known designs of pencil sharpener, in each of which the subject-matter of the present invention has been embodied.

Fig. 3 is a detail view of the flexible strip or collar used in producing the chip receptacle of Fig. 2; and

Fig. 4 is a top plan view of the form of receptacle shown in Fig. 2.

1, 2, represent the framing members, preferably of sheet metal, constructed with opposed inturned flanges 1^a, 2^a, and spaced apart and connected in mutually sustaining relation by the cross bars 3. Located between these framing members 1, 2, and confined by the flanges 1^a, 2^a, thereof, is a wall forming strip or collar 4 of transparent celluloid or the like. Upon the inner surface of all that part of the collar 4 which should be obscured, ornamented, and protected from abrasion, is applied a sheath 5 of pigment, preferably printers' color, that serves the several purposes hereinbefore stated. If it is desired to imprint upon the receptacle 75 any letter press matter such as the maker's trade-name, the dealer's advertisement, any design or the like, this is done preliminarily to imprinting the sheath, and the latter then serves as a protecting backing, a setting-off 80 background, or color field for such matter. 75

I claim:

1. A chip receptacle and casing for pencil sharpeners comprising spaced and mutually sustaining framing members, an intervening 90 strip of wall-forming transparent material sustained between said framing members, and an obscuring, protecting, and coloring sheath of pigment applied as a backing to, and protecting and rendering non-transparent the bottom and side forming portions of said strip, and receiving its surface gloss from the surface thereof.

2. The improvement in the art of ornamenting and protecting transparent walls 100 of chip receptacles, which consists in impressing thereon, upon the portion to be protected, a sheath of pigment in position to resist impingement of chips deposited thereinto, and in position to reflect through 105 the transparent material of the wall and receive surface gloss therefrom.

Signed at Chicago, Illinois, this 10th day of March, 1921.

EMORY S. ENSIGN.
